ALTERNATING CURRENT IONIZATION CHAMBER

Robert E. Fearon, Tulsa, Okla., assignor to Well Surveys, Incorporated, Tulsa, Okla., a corporation of Delaware

Application June 22, 1948, Serial No. 34,488

9 Claims. (Cl. 250—83.6)

1

This invention relates generally to the art of geophysical prospecting and more particularly to radioactivity well logging.

Specifically this invention is directed to a method and apparatus for making an ionization chamber generate alternating current by controlling the circulation of the ionizable medium in a convection type ionization chamber, such as that disclosed in my copending application Serial Number 572,666 now Patent No. 2,472,153.

The convection type ionization chamber employs an ionizable medium such as argon or helium which contains a trace of a substance, such as xenon, which reduces the electrical mobility of the positive ions without affecting the electrical mobility of the negative ions. This ionizable medium is circulated continuously in the system by a pump. At one point in the system the medium is completely de-ionized, then the ionizable medium is subjected to the gamma radiation that it is desired to measure. The gamma radiation entering the ionizable medium produced ionization thereof. The area in which the ionization occurs has disposed therein collector plates to which the negative ions diffuse immediately while the more cumbersome positive ions, by the circulation of the ionizable medium, are swept out of this area and into a third area where de-ionization is affected. A measurement of the current produced by collecting either the negative or positive ions is a measurement of the gamma radiation which produced the ionization.

It is obvious, that since the operation of the detector described above depends on the propulsion of the ionizable medium, the ionization current would fall to a much smaller value if the ionizable medium was at rest. Consequently, if the circulating pump is so arranged that it delivers a current of the ionizable medium intermittently, the output of the electrical system would vary in a corresponding manner. For example, assuming that the operation of the pump occurs in cycles of one second of pumping and one second of not pumping, it is apparent that the output of the electrical system will contain a component of alternating current at one-half cycle per second, inasmuch as two seconds are needed for the cycle which has been ascribed to the pump.

There are many ways of causing the current of the ionizable medium to flow intermittently. As examples: an ordinary reciprocating piston-type pump, or centrifugal pump of the type employed in sirens, using as the output any one of

2

the peripheral ports. Another way of producing intermittent flow of the ionizable medium through the area in the system in which the gamma rays are detected is by opening and closing a valve in a pipe which acts as a shunt across the circulating pump. If such a valve is closed, the current of the ionizable medium will pass through the usual delivery channel of the pump, and if the valve in the shunt line is open, the ionizable medium will pass through the shunt line thereby reducing the delivery, as would be observed in the normal delivery channel of the pump, to a very small value. Accordingly cyclical openings and closings of the valve in the shunt line will produce cyclical variation in the electrical output which appears from the ionization chamber. It is obvious that similar results could be obtained by placing a valve directly in the delivery line of the pump and opening and closing it cyclically.

20 The choice of frequency to be employed in interrupting the flow of the ionizable medium would depend upon the spacing of the plates in the zone of the instrument where the electrons are collected by diffusion. The frequency will also depend on the length of this group of plates parallel to the direction of the flow of the ionizable medium. The choice of frequency will also be influenced by the diffusibility of both the positive and negative ions. Generally speaking, the upper limit of the required frequency will be fixed by the diffusibility or electrical mobility of the electrons in the working medium, while the lower limit of the operating frequency will be fixed by the diffusibility or electrical mobility of the positive ions in the ionizable medium. The amplitude of movement of the medium corresponding with an interval of pumping should be enough to sweep out the medium from between the working plates which collects the electrons.

45 The working plates which collect the electrons will be replaced by a system of small tubes. An equivalent will also be a mass of steel wool or shavings, or, in fact, any shaping or conformation of electrically conducting matter having fine openings between metal surfaces, and disposing an extensive area of metal surface in a small amount of volume.

50 The way in which the desirable operating frequencies can be fixed, can easily be understood if the fundamental principle, that every photo-electron which occurs in the zone of the electron collecting plates must contribute to the output current, is remembered. Assume for the

moment that the ionizable medium has ceased to flow between the negative ion collecting plate. The electrons which are thus produced as one member of ion pairs quickly disappear by diffusion to the nearest metal surface. This continues for a period of time until the positive ions also begin to disappear by diffusion to the metal surfaces. If the movement of the ionizable medium begins again before any large fraction of the positive ions have thus been lost most of these ions will be swept out of the plates. If the flow had recommenced too quickly to permit the electrons to be lost by diffusion the electrons along with the positive ions would have to be swept out, which would result in no net charge being carried to the collecting plates and hence no electrical output would result. It is accordingly necessary to permit the ionizable medium to remain at rest sufficiently long to lose a very large fraction of the electrons which occurred during the rest period but not sufficiently long to bring about an appreciable loss of positive ions. The interval of the flow must be approximately equal to the interval of the rest for the greatest electrical output at the fundamental frequency of the cyclic process.

There are, moreover, other limitations on the frequency choice which depend on the intensity of the radiation being detected. Intense radiation will not be satisfactorily registered by low frequency circulation for the reason that the electrons will not be lost by diffusion if too many positive ions remain during an interval, because of space charge effect of the residual positive charge.

Therefore the principal object of this invention resides in the provision of a method and apparatus for detecting ionizing radiation, such as gamma rays, by producing an alternating current whose amplitude is a measure of the ionizing radiation.

Another object of this invention resides in the provision of an ionization chamber adapted, on exposure of radiation, to deliver an alternating current output.

Still another object of this invention resides in the provision of a convection current type ionization chamber which, when exposed to ionizing radiation, will deliver alternating current.

This invention also contemplates a method of producing alternating current in an ionization chamber by causing the ionizable medium therein to circulate in pulses cyclically.

Another object of this invention resides in the provision of novel means for detecting extremely weak penetrating radiations, such as gamma rays, by generating an alternating current whose amplitude is directly proportional to the penetrating radiation.

Other objects and advantages of the present invention will become apparent from the following detailed description when considered with the drawings in which.

Figure 1 is a diagrammatic illustration of one form of the present invention illustrating the use of a pump for circulating the ionizable medium by pulses;

Figure 2 is a diagrammatic illustration of the second form of the present invention showing the use of a valve in the supply line from the pump for controlling the pulses in the ionizable medium;

Figure 3 is a diagrammatic illustration of a third form of the instant invention illustrating

the use of a valve in the shunt line of a pump; and

Figure 4 diagrammatically illustrates a still further modification of the present invention in that the multiple detectors are employed in producing the alternating current.

Referring to the drawings in detail, particularly Figure 1, there is illustrated an ionizable medium circulating system 10, having a pump 11, that is adapted on operation to circulate the ionizable medium in the direction indicated by the arrows. The ionizable medium may consist of a gas, such as argon, plus a trace of propylamine. The trace of xenon is added to the gas to reduce the electrical mobility of the positive ions. The gas being circulated in the form of pulses by the pump 11, passes through a set of de-ionizing plates 12, of which every other plate is made positive with respect to ground by means of a battery 13. Those plates which are not positive with respect to ground, are connected to the ground and to the negative terminal of the battery 13. The electrical field between the plates 12 is made sufficiently strong to sweep all ions from the circulating gas. The gas flowing through the plates 12, is thus completely de-ionized, and on reaching the zone occupied by a second set of plates 14, becomes subjected to the gamma radiation that it is desired to measure. The gamma radiation causes the gas to become ionized. Since the electrons have considerably more diffusibility than the positive ions they will be immediately absorbed by the plates 14. The reduced diffusibility or electrical mobility of the positive ions, due to the propylamine, will cause them to be carried out of the zone occupied by the plates 14, into the zone occupied by a third set of plates 15. Every other one of the plates 15, are connected to the positive side of the battery 16, and the remaining plates are connected to the negative side of the battery 16, and to ground. The plates 15, in the manner described in connection with the plates 12, also function as means for de-ionizing the gas as it passes over them.

The electrons absorbed by plates 14 produce a flow of current in the conductor 17, through the input of amplifier 18 to ground at 19. Due to the fact that no surge chamber is provided the gas will flow in pulses and as a result the current produced will be a pulsating current having a frequency that is equal to the number of strokes of the pump 11 per second. The alternating component of the signal thus produced in the input of amplifier 18 is amplified at the frequency of alternation of the pump and indicated or recorded by the meter or recorder 20 as a measure of the gamma radiation entering the region of the plates 14.

In Figure 2 there is illustrated a modification of the present invention. This form of the invention differs from that shown in Figure 1 in that a valve 21 is disposed in the ionizable medium circulatory system 10 on the exhaust side of the pump 11. Valve 21 is caused to open and close at a predetermined rate by the synchronous motor 22 which drives it through the gear box 23. Gear box 23 is equipped with a plurality of gears whereby the speed at which valve 21 is opened and closed can be varied at will to control the frequency of pulsation of the gas flow and thereby control the frequency of the signal amplified and recorded by the amplifier 18 and the recorder 20.

Still another embodiment of this invention is illustrated in Figure 3. In this form of the in-

vention the circulatory system 10 is provided with a by-pass 24 which permits the gas being circulated by the pump 11 to by-pass the plates 12, 14 and 15. A valve 25 is disposed in the by-pass 24. Valve 25 may be driven by a synchronous motor 26 through a gear box 27 in the same manner as described in connection with Figure 2 to produce pulsations in the flow of gas over the plates 12, 14 and 15. In this form of the invention, as well as those illustrated by Figures 1 and 2, the useful signal is produced by diffusion of electrons to the plates 14.

Another embodiment of the present invention is illustrated in Figure 4. In this form of the invention the circulatory system 10 is arranged to provide two like paths 26 and 27 for the flow of gas. Each path is provided with a similar set of plates which function in the same manner as those described above in connection with Figures 1, 2 and 3. The plates in path 26 have the same reference characters as used in the preceding figures and the plates in path 27 have the same characters with primes added. The battery 13 is used for both sets of plates 12 and 12' and the battery 16 is used for both sets of plates 15 and 15'. The plates 14 and 14' are connected to opposite sides of the input of a push-pull amplifier 28 which in turn is connected to the recorder or indicator 29.

In the operation of this form of the invention the pump 11 continually forces the gas toward a valve 30 which is disposed in a Y formed by the circulating paths 26 and 27 and the path leading from the pump. Valve 30 may be of the rotary type and be driven by a synchronous motor 31 through a speed control gear box 32. The ports in the valve are so arranged that the valve intermittently passes the current of gas supplied by pump 11 into path 26 and path 27. The currents produced by diffusion of electrons on the separate groups of plates 14 and 14' are brought by separate leads to the opposite sides of the push-pull amplifier 28 which impresses an alternating current signal at the frequency of operation of the valve 30 on the indicator or recorder 29 which indicates or records the intensity of the alternating current signal as an indication of the gamma rays falling on the two sets of plates 14 and 14'.

Although the present invention finds broad application in industry it is to be understood that it is particularly applicable to well surveying systems. The manner of incorporating the present invention in a well surveying system, except for small changes, is the same as that disclosed in my copending application Serial Number 572,666.

I claim:

1. A detector of ionizing radiation comprising in combination means defining a closed circulatory system, at least a portion of which is adapted to admit ionizing radiation, an ionizable medium in said system, means for circulating said medium in the system to expose it to the admitted radioactive ionizing emanations, said means being adapted to impart surges to said ionizable medium that are separated by uniform time intervals, means for de-ionizing said medium before it enters the portion adapted to admit ionizing radiation, means for separating the ions produced by said radiation when the medium enters that portion, means for collecting one group of the separated ions, and means for measuring the alternating component of the electrical current produced by the collection of said ions as a measure of radiation.

2. An apparatus for detecting penetrating radiation that comprises in combination a sealed system, an ionizable medium in said system, means for cyclically circulating said medium in said system, said means being adapted to impart surges to said medium which are separated by uniform time intervals, means in the path of said medium for de-ionizing said medium, said system having a zone in which the penetrating radiation enters the ionizable medium to produce ionization of the de-ionized medium, means adjacent said zone for collecting the negative ions, means at another point in the path of circulation of said surging medium for subsequently collecting the positive ions, and means for amplifying and recording the alternating component of the current produced by the collection of the negative ions.

3. An apparatus for detecting penetrating radiation that comprises in combination a sealed system, an ionizable medium in said system, means for circulating said medium, said circulating means being adapted to impart surges to said medium separated by uniform time intervals, means in the path of said medium for de-ionizing said medium, means for separating positive and negative ions formed by subjecting the de-ionized medium to penetrating radiation, and means for recording the alternating component of the current produced by collecting the separated negative ions as an indication of the intensity of the penetrating radiation.

4. An apparatus for detecting penetrating radiation that comprises in combination a sealed system, an ionizable medium in said system, means for circulating said medium, said circulating means being adapted to impart surges to said medium separated by uniform time intervals, means in the path of said medium for de-ionizing said medium, means for separating positive and negative ions formed by subjecting the de-ionized medium to penetrating radiation, and means for recording the alternating component of the current produced by collecting one group of the separated ions as an indication of the intensity of the penetrating radiation.

5. A detector of radioactive emanations comprising in combination a closed circulatory system; an ionizable medium in said system; means for circulating said medium in said system; said circulating means being adapted to impart surges to said medium that are spaced from each other by uniform time intervals; said circulatory system having in succession in the path of the circulating ionizable medium, a de-ionizing zone, an ionizing zone, and a second de-ionizing zone; de-ionizing means in each of said de-ionizing zones; means in said ionizing zone for separating the positive and negative ions produced by the action of radioactive emanations of said ionizable medium; means for collecting one group of the separated ions; and means for recording the alternating component of the electrical current produced by the collection of one group of ions as a measure of the radioactive emanations.

6. An apparatus for detecting penetrating radiation that comprises in combination a sealed system, an ionizable medium in said system, a pump in said system for circulating said medium in surges that are spaced from each other by uniform time intervals, means in the path of said medium for de-ionizing said medium, means for separating positive and negative ions formed by subjecting the de-ionized medium to the pene-

trating radiation, means for collecting the negative ions, and means for recording the alternating component of the current produced by collecting the separated negative ions as an indication of the intensity of the penetrating radiation.

7. An apparatus for detecting penetrating radiation that comprises in combination a sealed system, an ionizable medium in said system, means in said system for circulating said medium in said system, means in the path of said medium for separating positive and negative ions formed by subjecting the medium to the penetrating radiation, means forming a part of the sealed system defining a medium path that shunts the separating means, means for intermittently diverting the circulating medium to the shunt path, means for collecting the separated negative ions, and, means for recording the alternating component of the current produced by collecting the separated negative ions as an indication of the intensity of the penetrating radiation.

8. An apparatus for detecting penetrating radiation that comprises in combination a sealed system, an ionizable medium in said system, said sealed system having means defining two circuits for said ionizable medium, means for alternately circulating said ionizable medium through the circuits, separate means in each circuit for separating positive and negative ions formed by subjecting the ionizable medium in each circuit to

the penetrating radiation, means for collecting the negative ions produced in each circuit, and means for conducting the current produced by collecting the separated negative ions in each circuit to opposite sides of a push-pull amplifier, and means for recording the output alternating current from the amplifier as an indication of the intensity of the penetrating radiation.

9. An apparatus for detecting penetrating radiation that comprises in combination a sealed system, an ionizable medium in said system, means for circulating said medium, said circulating means being adapted to impart surges to said medium separated by uniform time intervals, means in the path of said medium for de-ionizing said medium, means composed of electrically conducting matter with small openings in it through which the ionizable medium circulates, such means to receive the radiation which it is desired to measure, and to which means the free electrons produced by the ionization will diffuse, but to which, because of lack of sufficient time, the positive ions will not diffuse the de-ionized medium to penetrating radiation, and means for recording the alternating component of the current produced by collecting one group of the separated ions as an indication of the intensity of the penetrating radiation.
